UNITED STATES PATENT OFFICE.

HENRY J. WIEGAND, OF MILWAUKEE, WISCONSIN, ASSIGNOR TO THE CUTLER-HAMMER MFG. CO., OF MILWAUKEE, WISCONSIN, A CORPORATION OF WISCONSIN.

MULTIPLE-SWITCH STARTER.

No. 913,865.

Specification of Letters Patent.

Patented March 2, 1909.

Application filed May 20, 1907. Serial No. 374,727.

To all whom it may concern:

Be it known that I, HENRY J. WIEGAND, a citizen of the United States, residing at Milwaukee, in the county of Milwaukee and 5 State of Wisconsin, have invented new and useful Improvements in Multiple-Switch Starters, of which the following is a full, clear, concise, and exact description, reference being had to the accompanying drawing, forming a part of this specification.

My invention relates to improvements in motor controllers. It is particularly applicable to controllers in which a plurality of hand operated switches are used to control a 15 resistance.

One of the objects of the present invention is to provide means whereby the motor circuit will be opened, unless all of the resistance is removed from circuit.

20 According to the preferred form of my invention, I provide a plurality of hand operated switches which are adapted preferably to be closed in a definite sequence to remove the starting resistance from circuit.

25 The starting resistance of devices of this character is usually constructed of wire, which while being of sufficient capacity to carry the current for a short time, is not of sufficient capacity to carry the current for 30 a long period of time. It is therefore desirable to provide some means whereby the operator can not close the circuit through the motor and the starting resistance, and go away and leave the controller in this condition.

35 To prevent such conditions from happening, in the present invention, one of the switches is adapted to control the motor circuit. I provide a low voltage retaining device for retaining this and the remaining 40 switches in their closed position, and to prevent the operator from leaving the starting device before all of the switches are closed and before all of the starting resistance has been removed from circuit, I provide a manu-

45 ally operated switch which either controls the circuit through the low voltage device or controls a short circuit around the same, and which, when, in one position renders the low voltage device inoperative, and when 50 in another position renders the low voltage device operative. The tendency of the manual switch is to move to a position to render the low voltage device inoperative and therefore during the closing operation

of the resistance controlling switches, the 55 operator must hold the small switch manually until the last switch of the series is closed. When the last switch of the series is closed, a second switch is operated which 60 renders the manual switch ineffective, and the low voltage device will retain the switches in their closed position.

While I have illustrated and described the preferred embodiment of my invention which I have worked out for practical operation, 65 it will be understood that my invention is susceptible to various modifications.

For the purpose of disclosing my invention, I have illustrated in the accompanying drawings a number of forms which the invention may take, and in said drawings: Figure 1 is a front elevation of one form of the switch of my invention. Fig. 2 is a side elevation thereof. Fig. 3 is a sectional top view of one of the levers, and a top view of 70 one of the coöperating rocking dogs. Fig. 4 is a detailed view of the latch mechanism for holding the levers in a closed position. Fig. 5 is a detailed view of one of the swinging dogs employed. Fig. 6 is a detailed view of 75 a modification of my invention. Fig. 7 is a diagrammatic view of the circuit arrangement. Fig. 8 is a diagrammatic view of a modified form of my invention, and Fig. 9 is a view of still another modification of my 80 invention.

In the embodiment of the invention illustrated, switch levers or arms 1, 1^a, 1^b and 1^c are suitably pivoted or journaled at one end, and at the opposite end are provided with 90 suitable operating handles. I have shown the several switch levers as journaled upon a shaft or rod 2, mounted in bearings upon brackets 3. The brackets 3 also support a rod 4 threaded through a rubber tube 5, 95 which serves as a cushion or buffer, against which the extended ends of the switch arms or levers are adapted to impinge, when thrown open. Each of the levers carries a contact device 6 made preferably in the 100 form of a number of strips of copper laid face to face, the free ends of which are adapted to engage contact surfaces to complete the circuit therethrough. The last lever 1^c of the series, in addition to the contact device 6, carries a contact 7, which may take the form of a pair of springs as shown 105 in the drawings, or any other desired form,

and which is suitably screwed or otherwise secured upon an insulating block 8, secured to the lever.

Upon the base board 9, which forms a support for the various parts of the switch, and which is preferably made of soapstone, slate or like insulating material, is mounted a contact bar 10, with which one end of the contact device of each arm or lever is adapted to engage, the other end of said device being adapted to engage terminals 11, 11^a, 11^b, and 11^c. The terminal 11^c is extended and carries a binding post 12 by which the same may be suitably electrically connected, as will be more fully hereinafter described.

Upon the terminal 11 is mounted a carbon block 13, and a similar carbon block 14 is mounted upon the end of the contact bar 10. The first switch arm carries laterally extending spring arms 15 and 16, which support upon their ends, carbon blocks 17 and 18. When the switch arm 1 is moved to close the circuit, the block 17 engages the block 13, and the block 18 engages the block 14, thereby closing the circuit from the terminal 11 to the terminal 10. The further movement of the switch arm 1 causes the contact device 6 thereof to directly close together the terminals 11 and 10. Likewise when the switch arm 1 is moved outward, the contact device 6 leaves the terminals 10 and 11 before the carbon contact blocks 17 and 18 leave the blocks 13 and 14, so that any arc that may form by the opening of the circuit will take place between the carbon blocks, instead of between the metallic surfaces.

Near the upper end of the switch arm 1, a lug 19 is provided, which carries a laterally extending rod 20, which may take the form 40 of a screw. Mounted upon the base board 9 and above the arm 1 is a retaining magnet 21, having an armature 22 pivoted at 23. The armature carries an upwardly extending lug 24 and when the arm 1 is moved to close 45 the circuit, the rod 20 engages the armature to move the same against the magnet pole where the mechanism of the magnet retains it. The swinging of the armature 22 carries the lug 24 upon the exterior of the rod 20 50 so that the rod will rest in the slot formed between the lug and the face of the armature, and as long as the magnet 21 remains energized, the arm 1 will thus be held in the closed position. When, however, the magnet 21 is deenergized, the armature 22 will be 55 released, and the weight of the arm 1 will carry the same to the position shown in Fig. 2.

Mounted upon a rod or shaft 25, supported 60 in suitable bearings upon the base plate 9, are rocking dogs 26, 26^a and 26^b. Each dog has its rear end so shaped as to engage the base plate 9 and limit the downward movement of the dog when free. Upon the end of 65 the dog, to the right hand side, an upwardly

extending lip 27 is provided, which has its front edge curved and its rear edge perpendicular to the upper surface of the dog. The under side of the dog has a lip 28, extending throughout its whole length which is rounded off at the left hand side. Each of the levers 1^a, to 1^c inclusive, is provided with a latch 29, pivoted to the arm or lever at 30, and set in a slot 31, the walls of which limit the vertical movement of the latch relatively to the 75 arm. Below the latch and formed integrally with the lever is a lug 32 projecting toward the base plate and consisting of two parts 33 and 34. The part 33 is square in section and flat upon the end and when the lever is in a 80 position to close the circuit presents a vertical surface. The upper face of the part 34 is inclined or chamfered at an acute angle.

In addition to the contact terminals 10 and 11^c, for the last switch 1^c, a pair of terminals 85 35 and 36 are mounted upon the base adapted to be engaged, when the last switch 1^c is closed, by the spring contacts 7. A small hand switch 38 is pivoted at the lower left hand corner of the base or panel and is 90 adapted to engage a contact 39 when moved by the hand. A spring 40, however, tends to maintain the switch in its normal or open position.

The mechanical operation of the switch 95 arms is substantially as follows during the starting operation. In starting the motor, the switch 38 is first closed and held by the operator against the tension of the spring 40. The closing of the switch 38 energizes the retaining magnet 21. The first arm 1 is now closed to first close the circuit and the carbon blocks 17 and 18 respectively engage the carbon blocks 13 and 14, thereby closing the circuit at this point. The further movement 100 of the arm causes the contact device 6 of the arm 1 to bridge the contact terminals 10 and 11. The armature 22 is engaged and moved against the pole of the retaining magnet 21 and the retaining magnet thus serves to 110 maintain the switch arm in a closed position as long as the switch 38 is held by the operator. In moving the arm 1 to a closed position the oblique wall 34 of the lug 32 engages the under face of the first rocking dog 26 and 115 swings the same into the position illustrated in full lines in Fig. 4. The operator, still holding the switch 38 closed with one hand, now by his other hand closes the arm 1^a, and as the dog 26 is in its raised position, the latch 29 will ride over the lip 27 of the dog and will engage the vertical wall thereof, and the switch arm 1^a will thus be held in a 120 closed position. The wall 34 of the arm 1^a will lift and engage the second rocking dog 125 26^a so that when the arm 1^b is closed, the latch 29 thereof will be engaged and held by the lip 27 of the dog 26^a. In a similar manner the remaining switches may be closed.

When the last switch 1^c is closed, the 130

spring contact 7 bridges the contacts 35 and 36 short circuiting the switch 38 and maintaining the circuit through the magnet 21 until the switch is again opened. In event, 5 the current through the magnet 21 fails for any reasons, the first switch 1 will immediately be released, which in moving outward, permits the first rocking dog 26 to fall and the latch of the second switch arm is thus 10 released and the switch arm flies outward. The switch arm 1^a permits the second rocking dog to fall, thereby releasing the third switch arm, and in a similar manner, each switch arm releases the next succeeding arm, 15 until all of the arms have been released, and the circuit opens.

Any attempt to close one of the switch arms out of its order will be prevented, due to the fact that the flat face 33 will engage 20 the end of the rocking dog when it is in its lower position, and it is only when the dog has been raised to the upper position that the flat face is permitted to pass beneath the end of the dog. Moreover unless the rocking dog 25 is in the upper position, the latch 29 will not engage the lip 27 on the dog, therefore the arms will be held in the upper position only when the preceding switch arm has been closed.

30 In Fig. 7 I have illustrated a diagrammatic view of the circuit arrangement of the device illustrated in Figs. 1 to 5. As shown in this figure the contact terminal 11^c is connected by a conductor 37, with one terminal 35 of the armature 38, the opposite terminal of the armature being connected with one side 39 of the supply main. One terminal of the shunt field winding is connected by conductor 41 with the negative side 39 of the 40 line, and the opposite terminal is connected by conductors 42 and 43 with the contact bar 10. One terminal of the winding of the magnet 21 is connected through the resistance 44 by conductor 45, with the contact 45 tact 35, which in turn is connected by conductor 46, with the contact 39. The switch 38 is connected by conductor 47, with the contact 36, which in turn is connected by conductor 48, with the negative side 39 of 50 the line. Between the terminals 11, 11^a, 11^b and 11^c a resistance 48 is connected, which is divided into sections and connected with each of the above mentioned terminals. A section 49 of resistance is also connected 55 between the contact 11^a and the contact 10. The terminal 11 is connected with the positive side 50 of the supply main.

In operation, after the operator has closed the switch 38, as soon as he closes the first of 60 the switches 1, circuit will be established from the positive side 50 to the contact 11, thence across the first switch 1, to the contact bar 10, thence by conductor 43, through the winding of the magnet 21, through the 65 resistance 44, by conductors 45 and 46,

across the switch 38, and by conductors 47 and 48, to the negative side 39 of the line. The magnet is thus energized and maintains the first switch in its closed position as has been previously pointed out. The closing 70 of the first switch 1^a also establishes a circuit from the positive side 50 of the line across the first switch 1, thence through the resistance 49, and all of the resistance 48, to the last terminal 11^c, and thence by conductor 37, through the armature 38, to the opposite side 39 of the line. The field circuit is also established from the conductor 43, by conductor 42, through the shunt field winding to the opposite side 39 of the line. 80 The motor thus starts with all the resistance in circuit, and as the remaining switches are closed, the resistance 49 is cut out and then the resistance 48, section by section, until all the resistance is removed from the motor 85 circuit, and the motor is running at full speed. When the last switch 1^c is closed, contact 7 bridges the contacts 35 and 36, thereby short circuiting the switch 38 and maintaining the circuit closed through the 90 winding of the magnet 21.

It may happen that an operator, after closing a portion of the switch arms, will neglect to close the remainder and will walk off releasing the switch 38. Under these 95 circumstances, it will be seen that as soon as the switch 38 is opened, the circuit through the magnet 21 is opened, which will permit all of the switch arms which have been closed to open again, thereby opening the circuit 100 through the motor. It will therefore be seen that it is impossible for a careless operator to cut out a portion of the resistance and leave the starter in this condition. The resistance of a starting device of this character 105 is usually constructed of wire, which while sufficiently heavy to carry the current for a short period of time while the motor is being started, is not usually of sufficient capacity to carry a current for a considerable period 110 of time, and it is therefore desirable to provide some means to prevent the leaving of a portion of a resistance in circuit for a considerable period of time. If during the starting operation the operator fails to 115 close all of the switches, he must hold the switch 38 closed in order that those switches which he has closed shall remain so, and under these circumstances, if the resistance is left in circuit for a considerable period of 120 time, he will be notified by the heating up of the resistance, and will therefore either remove all of the resistance from circuit by closing the remaining switches or open the circuit through the motor. It is therefore 125 seen that by this construction it is impossible for a careless operator to close a portion of the switches and go off leaving them in this condition. The operator must close all of the switches before permitting the switch 38 130

to open or as soon as he permits the switch 38 to open, the switches which he has closed will drop back to normal position.

In Fig. 8 I have illustrated a modification 5 of my device wherein a short circuit is established around the magnet 21, as long as the last switch arm is left open, which short circuit, however, is opened by the switch 38. In this form of my invention the last switch 10 1° carries a spring contact 51, which while the switch is open is adapted to engage the stationary contact 52. The stationary contact 52 is connected by a short conductor 53, with the switch 38, and the contact 39 of 15 the switch is connected by a conductor 54, with one terminal of the winding of the magnet 21. This terminal is also connected by a conductor 55, through the shunt field 40 of the motor, to the negative side 39 of 20 the line. The other connections for the motor are similar to those of Fig. 7. In Fig. 8, however, the magnet 21 is shown as being connected in series with the shunt field 40. In the operation of the modification illustrated in this figure when the first switch 1 is closed, circuit is established from the positive side 50 of the line, across the switch arm 1, through all the resistance and through 25 the motor armature as described with respect to Fig. 7. Circuit is also established from the contact 10, by conductor 43, through the winding of the magnet 21, and by conductor 55, through the shunt field 40 of the motor, to the opposite side 39 of the 30 line, that is, a circuit is thus established as long as the operator holds the switch 38 open, the normal tendency of this switch 38 being to close. If for any reason the operator permits the switch 38 to close, then a 35 circuit around the magnet will be established from the contact 10, across the spring switch 51, which as long as the last switch 1° is open, remains closed, by conductor 53, across the switch arm 38, by conductors 54 and 55, 40 through the shunt field 40, to the opposite side 39 of the line. It will thus be seen that the magnet 21 is deenergized, permitting the switch arms to drop to their open position. When the last switch 1° is closed, the switch 45 50 51 is opened, thereby opening the short circuit around the magnet at this point and rendering the switch 38 ineffective. This switch therefore may be permitted to spring to its normal or closed position without 55 affecting the magnet 21.

In Fig. 9 is shown still another modification of my invention in which instead of using a double contact switch as illustrated with respect to Fig. 7, a single contact 60 switch is used. In the device used for this modification, the last switch arm 1°, instead of carrying double switch contact, as shown at 7, carries merely a single switch contact adapted to engage with a single switch contact 65 56, which is connected by a conductor

57 with the contact 39 of the switch 38. The operation of the device according to this figure in closing the circuit of the motor, and in closing the circuit through the magnet 21, is similar to that described with respect to Fig. 7. When the last switch 1°, however, of the device is closed, circuit is established from the contact 10, through the arm 1°, by conductor 57, thence by conductor 58, through the winding of the magnet 21, instead of from the contact 10, by conductor 59, across the switch 38. It will thus be seen that the operator may permit switch 38 to move to its normal or open position when the last switch 1° is closed, but if he permits the switch to move to its open position before the last switch 1° is closed, the magnet will be deenergized, opening all of the switches which have been closed by him.

Having thus described my invention what I claim as new and desire to secure by Letters Patent is:

1. The combination with a plurality of switches, of a retaining means for holding all of said switches in closed position, and means independent of said switches adapted to be manually operated to render said retaining means effective and adapted to render said retaining means ineffective if released before certain of said switches are closed. 95

2. The combination with a plurality of switches tending to stand in open position, of a retaining means for holding all of said switches in closed position, means independent of said switches adapted to be manually operated to render said retaining means effective and adapted to render said retaining means ineffective if released before certain of said switches are closed, and means operated upon the closure of one of said switches for maintaining said retaining means effective, irrespective of the position of said manually operated means. 100

3. The combination with a plurality of switches, of an electro-responsive means for retaining all of said switches in closed position, and means adapted to be manually operated to render said electro-responsive means operative, and adapted to render said electro-responsive means inoperative if released before certain of said switches are closed. 110

4. The combination with a plurality of switches tending to stand in open position, an electro-responsive means for retaining said switches in closed position, means adapted to be manually operated to render said electro-responsive means operative and adapted to render said electro-responsive means inoperative if released before certain of said switches are closed, and means operated upon the closure of one of said switches for maintaining said electro-responsive means operative, irrespective of the position of said manually operated means. 120

5. The combination with a plurality of switches tending to stand in open position, of a retaining magnet for holding one of said switches in closed position, means for holding the remaining switches in closed position and adapted to release the same when said first mentioned switch is released and an independent switch adapted to be manually operated to render said retaining magnet 10 effective and to render said retaining magnet ineffective if released before all of said switches are closed.

6. The combination with a plurality of switches tending to stand in open position, 15 means insuring the closure of said switches in a definite sequence, a retaining magnet for holding the first switch of the sequence in closed position, means for holding the remaining switches in closed position and 20 adapted to be rendered ineffective upon the opening of the first switch of the sequence, an independent switch adapted to be manually operated to cause said magnet to be energized and to cause said magnet to be deenergized if released before all of said first 25 mentioned switches are closed and means operated upon the closure of the last switch of the sequence for maintaining said magnet energized, irrespective of the position of said 30 manually operated switch.

7. The combination with a plurality of switches, of a retaining magnet therefor, a manually operated switch for causing an operative current to flow through said magnet during the closing operation of said switches, and a switch operated by the closing of the last switch for causing an operative current to flow through said magnet.

8. The combination with a plurality of 40 switches, of a retaining magnet therefor, a manually operated switch for causing an operative current to pass through said magnet and having a tendency to move to an inoperative position, and a switch operated 45 by the closing of the last of the switches for causing an operative current to pass through said magnet.

9. The combination with a plurality of 50 switches, of a retaining magnet for holding one of said switches in a closed position, a plurality of interlocking devices for holding the remaining switches in a closed position, manually operated means for rendering said retaining magnet effective until the last 55 switch is closed, and means operated upon the closure of the last switch for maintaining said magnet energized.

10. The combination with a plurality of switches tending to stand in open position, 60 means insuring the closure of said switches in a definite sequence and for causing each switch, when closed, to hold a succeeding switch in closed position, a retaining magnet for holding the first switch of the sequence 65 closed, an independent switch adapted to be

manually operated to cause said magnet to be energized and to cause said magnet to be deenergized if released before all of said switches are closed and an auxiliary switch adapted to be operated upon the closure of 70 the last switch of the sequence for rendering said independent switch ineffective to cause the deenergization of said magnet.

11. The combination with a plurality of switches, of interlocking mechanism whereby each switch controls the next succeeding switch, a retaining electromagnet for holding the first switch, manually operated means which must be operated during the closing operation to render said retaining electro 80 magnet operative, and means for maintaining said retaining magnet operative when the last switch is closed.

12. The combination with a plurality of switches, of a retaining magnet for holding 85 the same, a switch for controlling said magnet having a tendency to move to inoperative position which must be held by the operator during the closing operation of said switches to render said magnet effective. 90

13. In a motor controller, the combination with a plurality of sections of resistance, a plurality of mechanically interlocking switches for controlling the same, said switches tending to stand in open position, 95 a retaining magnet for holding said switches in closed position, a switch adapted to be manually operated to cause said magnet to be energized and adapted to cause said magnet to be deenergized if released before all of said first mentioned switches are closed.

14. In a controlling device for electric motors, the combination with a plurality of 105 sections of resistance, a plurality of mechanically interlocking switches for controlling the same, said switches tending to stand in open position, a retaining magnet for holding said switches in closed position, a switch adapted to be manually operated to cause said magnet to be energized and adapted to cause said magnet to be deenergized if released before all of said first mentioned switches are closed and a switch operated upon the closure of the last switch 110 of the sequence for maintaining said magnet energized independently of said manually controlled switch.

15. In a controller for electric motors, the combination with a plurality of switches tending to stand in open position, one of 120 said switches being adapted to control the motor circuit, a plurality of sections of resistance adapted to be controlled by the remaining switches, means insuring the closure of said switches in a definite sequence, a retaining magnet for holding the motor circuit controlling switch in closed position, means for holding the remaining switches in closed position, said means being adapted to 125 130

be rendered ineffective upon the release of said circuit controlling switch, and an independent switch adapted to be manually operated to cause said magnet to be energized and adapted to cause said magnet to be deenergized if released before all of said first mentioned switches are closed.

16. In a controller for electric motors, the combination with a plurality of switches tending to stand in open position, one of said switches being adapted to control the motor circuit, a plurality of sections of resistance adapted to be controlled by the remaining switches, means insuring the closure of said switches in a definite sequence, a retaining magnet for holding the motor circuit controlling switch in closed position, means for holding the remaining switches in

closed position, said means being adapted to be rendered ineffective upon the release of said circuit controlling switch, an independent switch adapted to be manually operated to cause said magnet to be energized and to cause said magnet to be deenergized if released before all of said switches are closed, 25 and means operated upon the closure of the last switch of the sequence for rendering said independent switch ineffective to cause the deenergization of said magnet.

In witnesss whereof, I have hereunto sub- 30 scribed my name in the presence of two witnesses.

HENRY J. WIEGAND.
